UNITED STATES PATENT OFFICE.

WALTER ROGERS, OF WEST ANNAPOLIS, MARYLAND.

SHUTTER-OPERATING DEVICE.

1,270,439.

Specification of Letters Patent. Patented June 25, 1918.

Application filed March 16, 1918. Serial No. 222,920.

To all whom it may concern:

Be it known that I, WALTER ROGERS, a citizen of the United States, residing at West Annapolis, in the county of Anne 5 Arundel and State of Maryland, have invented certain new and useful Improvements in Shutter-Operating Devices, of which the following is a specification, reference being had to the accompanying drawings.

10 This invention relates to an improved device for opening or closing window shutters without necessitating that the window sash be raised.

It is the primary object of the invention 15 to provide a device for the above purpose which may be readily attached to the ordinary window shutter and which can be easily and quickly operated to move the shutters to their open or closed positions.

20 It is another and more particular object of the invention to provide shutter opening means including a manually operable element movably mounted in the sub-sill of the window frame, members hingedly connected to the respective shutters, and operating connections between said members and the manually operable element.

It is another object of my invention to 30 provide coacting means upon one of the shutters and said operating member whereby the shutters may be securely locked in their closed positions.

And it is a further general object of the invention to provide a shutter operating 35 device consisting of relatively few parts of simple form, and which will therefore be strong and durable and not likely to get out of order, and capable of manufacture at relatively small cost.

40 With the above and other objects in view the invention consists in the improved combination, construction and relative arrangement of the several parts, as will be herein-after more particularly described, subsequently claimed, and illustrated in the accompanying drawing wherein,

Figure 1 is a top plan view partly in section showing the shutters locked in their closed positions;

50 Fig. 2 is a similar view showing the relative positions of the parts when the shutters are open;

Fig. 3 is a section taken on the line 3—3 of Fig. 1;

Fig. 4 is a section taken on the line 4—4 55 of Fig. 1; and

Fig. 5 is a detail perspective view of the hingedly connected plates and the pintle therefor.

Referring in detail to the drawing, 5 designates the hinge plates which are suitably secured to the inner faces of the respective shutters, shown at S, adjacent to the lower edges thereof. Each of these plates has a sleeve or knuckle 6 formed on one of its ends to receive one arm of an angular pintle 7. The other arm of this pintle is engaged in a similar sleeve or knuckle 9 formed on one end of a plate 8.

An operating rod or lever 10 is longitudinally movable through an opening in the sub-sill of the window frame, and this rod terminates at one of its ends in an angular finger 11, a suitable head or operating handle 12 being fixed to the other end of said rod. Upon the rod 10, adjacent to the finger 11, a collar 13 is engaged and is held against longitudinal shifting movement by the cotter pins or keys 14 engaged through openings in said rod at opposite sides of the 80 collar.

To the collar 13 at diametrically opposite points the levers 15 are pivotally connected at one of their ends. Each of these levers intermediate of its ends is provided with a longitudinally extending slot 16 to receive a guide stud or screw 17 which is fixed in the sub-sill. The end of the lever beyond this slot is provided with a plurality of spaced openings 18.

19 designates rods or bars which are respectively connected by bolts 20 to the levers 15, said bars 19 being also provided with spaced openings 21 to register with a selected opening 18 in the lever 15 for the reception of the pin 20. Thus the bars 19 can be longitudinally adjusted with respect to the levers 15 in accordance with the width of the window frame. The bars 19 are connected at their other or outer ends to the 100 plates 8 by means of pivot pins 22. The plates 8 are also provided with additional openings 23 to receive the pins whereby the bars 19 can be adjustably connected to the respective plates.

To the frame molding of the window a plate 24 is secured, said plate having an opening 25 coinciding with the opening in

the sub-sill through which the operating rod 10 extends. This rod is provided on its lower side with a longitudinally extending series of teeth 26 which are adapted to engage the edge of the opening 25 and hold the rod against movement when the shutters are open.

To the inner face of the right hand shutter having the bead on its free vertical edge 10 for engagement in the rabbet or groove in the outer face of the other shutter when the shutters are closed, a keeper member 27 is fixed, and in this keeper member the terminal finger 11 on the rod 10 is adapted to 15 be engaged when said rod is turned after the shutters have been closed. The levers 15, the connected ends of the bars 19 and the outer end of the rod 10 are preferably inclosed within a suitable housing or casing shown 20 at 28, to protect the parts against injury from the elements.

From the foregoing description taken in connection with the accompanying drawing, the construction, manner of operation and 25 several advantages of the device will be fully understood. When it is desired to open the shutters, the operator first turns the rod 10 to the left to disengage the angular end 11 thereof from the keeper 27. He then pulls 30 inwardly on said rod, which transmits a pivotal sliding movement to the levers 15 and through the medium of the connecting bars 19, the shutters are urged outwardly to their open positions. The operator then 35 presses downwardly on the inner end of the handle or lever 10 to engage one of the teeth thereon with the lower edge of the opening in the plate 24. The reverse of this operation will close the shutters. Thus the inner 40 end of the handle is first lifted and the handle then forced outwardly so that the bars 19 are actuated and operate through the hinge plate 8 to pull or draw the shutters inwardly to their closed positions. The rod 45 10 is then turned to the right to engage the end 11 in the keeper 21 and thus securely lock the shutters against opening movement. It will thus be seen that I have produced a device which can be conveniently actuated 50 with a minimum of exertion from the interior of a room to either close or open the shutters without requiring that the window sash shall first be raised. The device as a whole is of exceedingly simple construction, 55 and the several parts thereof highly effective and reliable in its operation. While I have herein illustrated a particular mounting and arrangement of the several elements as well as the preferred form and construction 60 thereof, it is nevertheless to be understood that in these respects the invention is susceptible of considerable modification, and I therefore reserve the privilege of adopting all such legitimate changes as may be fairly

embodied within the spirit and scope of the 65 invention as claimed.

I claim:

1. A device for opening and closing shutters including a rectilinearly movable operating member, elements connected to the respective shutters for movement relative thereto, means operatively connecting said elements to the operating member, whereby in the movement of said member in one direction the shutters are closed and in the 75 movement of said member in an opposite direction the shutters are opened, and a keeper element fixed to one of the shutters with which the operating member is adapted to 80 coact to lock the shutters in their closed positions.

2. A device for opening and closing window shutters including a rectilinearly movable operating rod, levers mounted for sliding pivotal movement and operatively connected to one end of said rod, members connected to the respective shutters for movement relative thereto, and means operatively connecting the levers to said members whereby in the movement of the rod in one direction the shutters are closed and in the movement of said rod in an opposite direction the 90 shutters are opened.

3. A device for opening and closing window shutters including a rectilinearly movable operating rod, levers mounted for sliding pivotal movement and operatively connected to one end of said rod, members connected to the respective shutters for movement relative thereto, and bars connected at 95 one of their ends to said members and adjustably connected at their opposite ends to the respective levers and whereby the shutters are closed upon a movement of the rod in one direction and opened when the rod is 100 moved in an opposite direction.

4. A device for opening and closing window shutters including a rectilinearly movable operating rod, levers mounted for sliding pivotal movement and operatively connected to one end of said rod, members connected to the respective shutters for movement relative thereto, bars connected at one of their ends to said members and adjustably connected at their opposite ends 115 to the respective levers and whereby the shutters are closed upon a movement of the rod in one direction and opened when the rod is moved in an opposite direction, and latch means for holding the rod against 120 movement when the shutters are open.

5. A device for opening and closing window shutters including a rectilinearly movable operating rod, levers mounted for sliding pivotal movement and operatively connected to one end of said rod, members connected to the respective shutters for movement relative thereto, bars connected at 125

one of their ends to said members and adjustably connected at their opposite ends to the respective levers and whereby the shutters are closed upon a movement of the rod 5 in one direction and opened when the rod is moved in an opposite direction, latch means for holding the rod against movement when the shutters are open, and a keeper element fixed to one of the shutters, said rod having

an angular terminal finger to engage in said keeper upon a turning movement of the rod to lock the shutters in their closed positions.

In testimony whereof I hereunto affix my signature in the presence of two witnesses.

WALTER ROGERS.
